UNITED STATES PATENT OFFICE

BEST PRATT, OF CHICAGO, ILLINOIS

QUICK RELEASE VALVE

Application filed November 22, 1929. Serial No. 409,047.

The present invention relates to improvements in the structure of valves of fluid pressure brake and signal mechanisms commonly termed "conductor's valve" or "quick release valve", and has for its object to provide a valve of the character referred to, which will be of extremely simple construction and very durable.

In the accompanying drawings, which illustrate one embodiment of the invention:

10 Figure 1 is a plan of the improved valve.

Figure 2 is a section substantially on the line 2—2 of Figure 1, showing the valve in normal position closing the outlet.

15 Figure 3 is a section at right angles to that in Fig. 2, showing the parts in an adjusted position, in which the valve is open.

Figure 4 is a plan of the valve member detached from the casing.

20 Figure 5 is a bottom or inner face view of the valve operating arm, detached.

Referring to the drawings, in the several figures of which like parts are designated by the same reference characters, it will be seen that the improvements comprise a casing 1, 25 provided with a suitable inlet port 2, and an outlet with which cooperates a valve 3.

The valve 3 is provided with a face plate 4 adapted to be forced against a valve seat 5 located about the inner end of the casing outlet. As shown, this seat is formed at the inner end of a sleeve 6, which is positioned within the outlet passage and the valve body is formed with an extension 7 that is longitudinally channeled or cut away to provide 35 escape passages 8.

A spring 9 within the casing normally holds the valve 3 in position against the seat 5 to close the outlet.

40 Movement of the valve in opposition to the spring 9 is effected by an arm 10, which is pivotally connected to a post 11 on the casing 1, so that it may rock or swing across the outer end of the outlet, and means are inter-

45 posed between this arm and the valve body, so that when the arm is turned in either direction from its normal position, shown in Figure 1, the valve will be moved inward to open the casing outlet.

50 As shown, a ball 12 is interposed between

the actuating arm and valve, being seated in a suitable socket formed in the outer end of the valve body and within a channel provided in the inner face of the arm and extending substantially concentric with the axis about 55 which it is adapted to turn.

The channel in the inner face of the arm 10 referred to comprises a central or mid-section 13 of maximum depth, in which the ball 12 is positioned when the valve is closed, 60 and sections 14 of said channel extending in diametrically opposite directions from said central portion 13 are of reduced depth, so that as the arm is turned, the ball 12 will pass from the portion 13 of said channel to one of 65 the portions 14 thereof, and thus force the valve inward from the position shown in Figure 2 to that illustrated in Figure 3.

Outward movement of the actuating arm 10 is prevented by providing a tongue 10a 70 thereon, which extends into a guideway or groove 15 formed in the casing 1.

By this arrangement the actuating arm is held against movement away from the casing and limited to swing in a plane extending 75 transversely of the outlet.

As shown, the free end of the arm 10 is apertured, as at 16, to receive either a suitable hand-piece, or a cord or cable, such as commonly provided in fluid pressure brake 80 or signal systems.

It is believed that the operation and advantages of the improvements will be readily understood from the foregoing description of the drawings.

It will be noted that the entire structure includes a minimum number of parts, all of which can be of strong and durable construction so that there is little or no danger of their becoming disarranged. The desired 90 movement of the actuating arm is readily effected and the entire structure is a very efficient one.

It will be noted that by manipulation of the arm 10, the valve may be held in either 95 a partially open or fully open position. That is, when the arm is turned so that the ball 12 is in contact with the shallower portion 14 of the groove in the underface of the arm, the valve will be moved from its seat, but 100

will not be fully opened. When, however, the arm is turned into the position shown in Figure 3 in which the ball is beneath the flat surface at either end of the groove 14, the 5 valve is depressed to the maximum extent.

I claim:

1. A quick release valve for the purpose described comprising a casing provided with an inlet and an outlet, a valve adapted to close 10 the outlet, an arm pivoted on the casing to move transversely of the outlet about an axis extending substantially at right angles to the plane of the outer end of the outlet, and means interposed between the arm and valve 15 whereby the latter will be moved to open the outlet as the arm is turned about its pivotal connection with the casing.
2. A quick release valve for the purpose described comprising a casing provided with an 20 inlet and an outlet, a valve within the casing adapted to close the outlet, an operating arm pivotally mounted on the casing to move across the outer end of the outlet, and means between the arm and valve whereby the latter will be moved to open the outlet as the arm is turned about its pivotal connection with the casing.
3. A quick release valve for the purpose described comprising a casing provided with 25 an inlet and an outlet, a valve seat at the inner end of the outlet, a valve adapted to cooperate with said seat to close the outlet, a spring acting to normally hold the valve against the seat, the valve having a member 30 extending into the outlet, an arm pivoted to the casing to move across the outer end of the outlet, and means interposed between the arm and valve member within the outlet for moving the valve in opposition to the spring 35 when the arm is moved about its pivot.
4. A quick release valve for the purpose described comprising a casing provided with an inlet and an outlet, a valve adapted to close the outlet, a spring acting to hold the valve in 40 closed position, an operating arm pivotally mounted on the casing to move across the outer end of the outlet and having formed in its inner face a channel extending substantially 45 concentric with its pivot, said channel being of greater depth near its middle than at its 50 ends, and a spherical shaped body arranged within said channel and contacting with the valve, whereby as the arm is turned about its pivot the valve will be moved in opposition 55 to the spring to open the outlet.
5. A quick release valve for the purpose described, comprising a casing provided with an inlet and an outlet, a valve adapted to close the outlet, an arm pivotally mounted on the 60 casing to move across the outer end of the outlet, a projection on said arm adapted to cooperate with the casing to limit movement of the arm about its pivot, and means between the arm and valve whereby the latter will be 65 moved to open the outlet as the arm is turned

about its pivotal connection with the casing.

6. A quick release valve for the purpose described, comprising a casing provided with an inlet and an outlet, a valve within the casing adapted to close the outlet, an operating arm pivotally mounted on the casing to move across the outer end of the outlet, the casing having formed therein a segmental channel concentric with the axis of the pivot of the arm, a projection on the arm extending into said channel, and means between the arm and valve whereby the latter will be moved to open the outlet as the arm is turned about its pivotal connection with the casing. 70

7. A quick release valve for the purpose described comprising a casing provided with an inlet and an outlet, a valve adapted to close the outlet, a spring acting to hold the valve in closed position, an operating arm pivotally mounted on the casing, and means interposed between the arm and valve, whereby the latter will be moved in opposition to the spring as the arm is turned about its pivotal connection with the casing, said means and arm being so related that the valve will be held in either of a plurality of different open positions in accordance with variations in the extent of movement of the arm in either direction from its position when the valve is closed. 80

8. A quick release valve for the purpose described comprising a casing provided with an inlet and an outlet, a valve adapted to close the outlet, a spring acting to hold the valve in closed position, an operating arm pivotally mounted on the casing and having formed in its inner face a channel extending substantially concentric with its pivot, and means supported by the valve and extending into said channel, the latter varying in depth at different points in its length, whereby as the arm is turned about its pivotal connection with the casing the valve will be moved in opposition to the spring and held in any one of a plurality of open positions according to the extent of turning movement of the arm. 90

In testimony whereof I have hereunto set my hand.

BEST PRATT.
